UNITED STATES PATENT OFFICE.

WILLIAM L. MURPHY, OF SAN FRANCISCO, CALIFORNIA. ASSIGNOR TO MURPHY WALL BED COMPANY, A CORPORATION OF CALIFORNIA.

FOLDING BED.

1,171,971.

Specification of Letters Patent. Patented Feb. 15, 1916.

Application filed January 29, 1912. Serial No. 674,145.

To all whom it may concern:

Be it known that I, WILLIAM L. MURPHY, a citizen of the United States, and a resident of the city and county of San Francisco, State of California, have invented certain new and useful Improvements in Folding Beds, of which the following is a specification.

The invention relates to beds which are 10 movable about a horizontal axis to either vertical or horizontal positions.

The object of the invention is to provide means for locking the bed in the horizontal position.

15 A further object of the invention is to provide means for relieving the supporting frame or structure from the weight of the bed when it is in the horizontal position.

Another object of the invention is to provide an improved structure for counterbalancing the weight of the bed as it is moved from one position to the other.

Another object of the invention is to provide an improved means for controlling the 25 head of the bed as the bed is moved.

The invention possesses other advantageous features, which, with the foregoing will be set forth in the following description, where I shall outline in full that form 30 of embodiment of the invention which I have selected for illustration in the drawings accompanying and forming part of the present description. The novelty of the invention will be included in the claims 35 succeeding said description. From this it will be apparent that I do not restrict myself to the showing made by such drawings and description as I may adopt many variations within the scope of my invention as 40 expressed in said claims.

Referring to the drawings; Figure 1 is a vertical section taken through the bed in the horizontal position, several of the parts thereof being broken away. Fig. 2 is a 45 similar view of the bed in the vertical position. Fig. 3 is a detail of one side of the bed at the head, showing the arrangement of the counterbalancing springs and the supporting legs. Fig. 4 is a detail view, 50 illustrating the position of the counterbalancing springs when the bed frame is extended.

The bed of my invention is of that class, 55 termed generally folding beds, which are pivoted or hinged to move about a horizon-

tal axis, so that the bed may be moved from a vertical position to a horizontal position and vice versa. The bed frame 2 is provided on opposite sides with lugs 3, on each of which is formed a cylindrical boss or stub 60 axle 4 which bears in the link 5. The link 5 is pivotally attached to the bracket 6 which is secured to the wall or other structure from which the bed is supported. In Figs. 1 and 2 I have shown the frame 6 secured to a carrying 65 frame 7 which is hinged to the vertical siding 8, of an opening in the wall so that when the bed is in the vertical position it may swing through the opening. The carrying frame 7 is particularly adapted to be 70 used when the bed is to be used in a bed of the disappearing type and may be formed integral with the supporting brackets 6, or the brackets may be attached thereto. When the bed is secured directly to a wall 75 or other permanent structure, the carrying frame 7 may be dispensed with and the brackets 6 attached directly to the wall or structure. It is preferable, however, to employ a structure similar to that shown to 80 provide a means for securely attaching the brackets to the wall or other support. By pivoting the link 5 to the bracket 6, the fulcrum or center of rotation of the bed is movable with respect to the carrying frame 85 7. When the bed is in the vertical position the link has moved so that the fulcrum lies at its position of closest approach to the carrying frame, thereby providing a compact structure. With the initial movement 90 of the bed from the vertical position the link 5 moves outward, carrying the fulcrum away from the carrying frame 7, so that the fixed head 11 on the bed frame, clears the carrying frame. The movement of the 95 link 5 is controlled by the pin 9 on the lug 3, operating in conjunction with the cam surface 12 which is preferably formed integral with the bracket 6. When the bed is in the vertical position the pin 9 bears 100 against the bottom of the groove 13 and the link 5 bears against the standard or guide 14 which carries the cam surface 12. The bed is thereby stopped from moving closer to the supporting structure and the foot 105 piece 15 is prevented from contacting with and marring the wall or other supporting structure. The fulcrum 4 is so placed that when the bed is in the vertical position, the center of gravity thereof lies between the 110

fulerum and the carrying frame 7. As the bed is moved downward from the vertical position, the pin 9 moving in the groove 13 causes the fulerum 4 to move outward. A further movement of the bed brings the pin in contact with the inclined cam surface 12. In passing over this surface the fulerum is drawn backward toward the supporting structure and the friction between the pin and the cam surface is increased. This friction acts as a partial counterbalance or brake for the descending bed and prevents it from descending too rapidly or from throwing the weight of the bed against the person lowering it. As the bed reaches the horizontal position the pin 9 drops into the seat 16 on the upper end of the standard 14, locking the bed in such position, so that it requires considerable upward pull on the foot of the bed to unseat the pin.

The bed is partly counterbalanced in its movement between the vertical and horizontal positions by the coiled springs 17 which are attached at one end to the angle iron 18 extending across the bed at the head and at the other end to the angle 19 which extends transversely between the brackets 6, said angle irons constituting anchoring means for the springs. When the bed is in the vertical position these springs are only in sufficient tension to prevent them from rattling and are extended as the bed moves downward. When the bed is in horizontal position the springs extend in a vertical direction between the front edges of the rails 18 and 19 to which the two ends of the springs are, respectively, attached. The line of pull of the springs then lies in front of the pins 9 so that the springs operate to hold the bed frame in horizontal position. The metallic mattress on the bed frame is preferably attached at the head end to the angle 18.

Pivottally attached to the lugs 3 are legs 21 which are of such length that they contact with the floor and support the head of the bed when it is in the horizontal position, thereby relieving the brackets 6 and the carrying frame of the load. These legs 21 are preferably adjustably attached to the lug 3 so that their position may be varied in order that they will operate properly to relieve the brackets 6 of the load at the proper time. This feature is important on account of the variable thickness of floor coverings and the varying positions of the brackets 6 above the floor in different installations. These legs are loosely pivoted to the lugs so that they always maintain a substantially vertical position. Pivottally attached to the foot piece 15 are legs 20 which also maintain a substantially vertical position, when the bed is in vertical or horizontal position.

The head frame 22 which is pivoted to the fixed head 11 by the stop hinges 23 is connected at the upper part with the carrying

frame 7 by means of the spring 24. The spring is of such length that it is slightly in tension, and thereby holds the head frame stationary, in either the vertical or horizontal positions of the bed. The spring is made of such size and dimensions that it is comparatively rigid under compression and, therefore, acts as a link to push the head frame forward or away from the carrying frame as the bed is moved from either position. The head frame is thereby prevented from contacting with the carrying frame as the bed is moved.

I claim:

1. In a folding bed adapted to be moved about a horizontal axis, brackets having upwardly extending portions arranged on opposite sides of the bed, a bed frame, links pivotally attached to said brackets and said bed frame, and means on the bed frame engaging said upwardly extending portions of the brackets, the links being arranged to swing backward against said upwardly extending portions to limit the backward movement of the bed frame when said frame is moved into vertical position.

2. In a folding bed, brackets, links attached to said brackets, a bed frame pivotally mounted on said links, freely swinging legs at the foot of the bed frame, legs adjustably arranged on the frame between the foot and the point of connection of the frame and links and adjacent said point, said legs being arranged to contact with the floor in advance of the legs at the foot as the bed is moved into a horizontal position and relieve the links of the weight of said bed frame.

3. In a folding bed the combination of brackets having upwardly projecting portions, a bed frame mounted on said brackets, links connecting said bed frame and brackets, said links being arranged to contact with said upwardly projecting portions when the bed frame is in the vertical position and pins on said frame adapted to seat in depressions on said upwardly projecting portions when the bed is in the vertical position.

4. In a folding bed, a pair of brackets, upstanding guides thereon, a bed frame having pins to coöperate with said guides, links connecting said frame and brackets, a transverse projection on said brackets, a transverse rail on the bed frame, a mattress secured to said rail, and a counter-balancing spring extending in a vertical direction between said rails and projection and arranged to lie in front of said pins when the bed is horizontal to aid in holding the bed in said position.

5. In a folding bed, a pair of brackets, projections extending vertically from said brackets, a bed frame carrying pins engaging said projections, links pivoted to said brackets and frame and arranged to move

- into a forwardly-inclined position when said frame is extended and to move back into substantial parallelism with said projections when said frame is closed, spring anchoring means carried, respectively, by said frame and brackets, and counterbalancing springs located back of said links and extending in a substantially vertical direction between said anchoring means, said springs being arranged to lie in front of said pins when the bed is extended to thereby aid in holding the bed in such position.
6. In a folding bed, a pair of brackets, stationary guides extending upwardly from said brackets, a bed frame having pivots engaging the rear portion of said guides, and other pivots carried by said frame, and links connecting the last-named pivots with said brackets and arranged to bear against the front portion of said guides when the bed frame is in vertical position.
7. In a folding bed, a pair of brackets having rigid guides projecting upwardly therefrom, a bed frame supported by four pivots, said pivots arranged to lie upon opposite sides of said guides at separated points and coöperating with the guides to prevent backward movement of the bed when in vertical position, and links extending from two of said pivots to said brackets.
8. In a folding bed, a pair of brackets having stationary guides extending upward with seats in their upper ends, a bed frame supported by four pivots, arranged on opposite sides of said stationary guides, the pivots on the rear side of said guides to lie in said seats when the bed frame is in a horizontal position, and counterbalancing springs fastened to the bed frame and brackets, their upper ends arranged to lie in front of said rear pivots when the bed is in a horizontal position to assist in holding said rear pivots in said seats, and back of said rear pivots when the bed is in a vertical position to assist in holding the bed in said position.
9. In a folding bed, a pair of brackets having stationary guides extending upwardly therefrom, said guides having open vertical slotted portions near their lower ends, a bed frame supported by four pivots arranged on opposite sides of said guides, and constructed and arranged to act at separated points against said guides when the bed is in vertical position to resist the tendency of said bed to move backward, the pivots on the rear side being arranged to lie in said slotted portions when the bed is in vertical position.

In testimony whereof, I have hereunto set my hand at San Francisco, California, this 23rd day of January 1912.

WILLIAM L. MURPHY.
